The ornamental design for a freestanding rack for supporting a recycling bag, as shown, and described.

DESCRIPTION

FIG. 1 is a perspective view, looking from above, of a freestanding rack for supporting a recycling bag;

FIG. 2 is a front elevational view thereof;

FIG. 3 is a rear elevational view thereof;

FIG. 4 is a left side elevational view thereof, the right side being a mirror image thereof;

FIG. 5 is top plan view thereof; and,

FIG. 6 is a bottom plan view thereof.
